UNITED STATES PATENT OFFICE.

THOMAS J. COO, OF TORONTO, ONTARIO, CANADA, ASSIGNEE TO THE MONARCH TYPE-WRITER COMPANY, OF SYRACUSE, NEW YORK, A CORPORATION OF NEW YORK.

TYPE-WRITING MACHINE.

949,463.

Specification of Letters Patent. Patented Feb. 13, 1910.

Application filed November 14, 1907. Serial No. 402,172.

To all whom it may concern:

Be it known that I, THOMAS J. COO, subject of the King of England, and resident of Toronto, in the county of York, Province of Ontario, and Dominion of Canada, have invented certain new and useful Improvements in Type-Writing Machines, of which the following is a specification.

My invention relates to typewriting machines and more particularly to devices for controlling the platen. Said devices are intended more especially for condensed record billing work but are likewise adapted for rapid and accurate feeding of envelopes, shipping tags, labels and the like.

One of the objects of the invention is to provide simple and efficient means of the character specified.

To the above and other ends which will hereinafter appear, my invention consists of the features of construction, arrangements of parts and combinations of devices to be hereinafter set forth and particularly pointed out in the appended claims.

In the drawings, wherein like reference characters indicate corresponding parts in the different views, Figure 1 is an enlarged detail end elevation showing a platen and platen carriage with certain of the novel devices of my invention shown applied thereto. Fig. 2 is a central, longitudinal sectional view of the same. Fig. 3 is an enlarged detail sectional view taken through the joints which connect the actuating handles to their carrier. Fig. 4 is a transverse sectional view taken through the platen and illustrating the paper feeding devices constructed in accordance with my invention. Fig. 5 is a fragmentary plan view of the same with parts broken away. Fig. 6 is a fragmentary enlarged detail front view showing the locking lever for the stops and some of the associated devices.

I have shown my invention embodied in the present instance in a Monarch machine, though it should be understood that the invention may be employed in other styles of typewriting machines.

The platen 1 has a right-hand platen head 2 secured by a screw 3 to the platen shaft 4 journalled in tubular bearing sleeves 5 secured by screws 6 in openings in end bars 7 and 8 which project forwardly from a rear cross bar 9, said end bars also being united by a connecting rod 10; the end bars, cross

bar and connecting rod constituting a platen frame or carriage. The left-hand platen head has a line spacing ratchet wheel 11 formed thereon and with which a line spacing pawl 12, actuated in the usual manner, 60 cooperates. Finger wheels 13 are secured to the platen shaft by screws 14. The construction thus far described constitutes part of the Monarch machine and a further description thereof is deemed unnecessary. A 65 sleeve 15 surrounds the platen shaft at the right-hand end thereof outside of the end bar 7. Said sleeve is secured to the platen shaft by a locking pin 16 which passes through openings in the sleeve and shaft. 70 A disk 17 is mounted to turn on the sleeve at one side of the locking pin 16 whereas a second disk 18 is free to turn on the sleeve at the opposite side of the locking pin.

An intermediate disk or carrier 19 is provided with locking openings 20 therein in which the ends of the locking pin 16 are situated in order to lock the disk or carrier 19 to turn with the sleeve and platen shaft. A friction plate 21 has a central key hole 75 slot or opening 22 therein as shown in dotted lines in Fig. 1. The contracted end of the key hole slot in the friction plate is adapted to be received within cut-outs 23 in the sleeve so that the bottom flattened walls of 80 the cut-outs will cooperate with the friction disk or plate to lock it to rotate with the sleeve and platen shaft. The outwardly turned arms or fingers 24 on the friction plate bear against the inner face of the disk 18 and force it into frictional contact with the carrier 19 and this carrier in turn is forced by the pressure of the spring plate 85 against the disk 17, which, in turn, is pressed against the inner face of a pinion presently 90 to be described. The construction is such that the carrier 19 is positively locked to rotate with the platen and the disks 17 and 18 are frictionally connected to rotate with the carrier 19 and with the platen. 95

A stop or pin 25 (Fig. 1) extends outwardly from the disk 18 whereas a like pin or stop 26 extends inwardly from the disk 17. This stop 26 is in the nature of a screw which takes into a tapped opening in the disk 17 and across the space between the disks 17 and 18 and engages at its untapped end in any one of a number of openings 18* in the disk 18 to hold the disks 17 and 18 against 100 relative rotation and to maintain the stops 110

23 and 26 in their adjusted relation. Both of the pins or stops 25 and 26 extend into the path of a stop 27 formed on and projecting radially from the carrier 19 to arrest the latter and the platen to which it is connected. The disk 18 is of greater diameter than the disk 17 and is provided with teeth 28 forming locking openings 29 between them. The openings 29 in the disk 18 correspond to the number of teeth employed on the line spacing ratchet wheel 11 and are adapted to receive the end 32 of a locking device or pawl 33, pivoted to the platen frame and provided with a forwardly extending finger piece 34. In the normal or inoperative position of the pawl or lever 33, the forward end of said lever is depressed and in this position the engaging end 32 of the pawl is out of engagement with the disk 17 and the disks 17 and 18, as well as the stop 27, are free to turn unlimited extents with the platen. When, however, the pawl engages in one of the openings 29 both of the disks 17 and 18 are locked against rotation and the stops 25 and 26 will arrest the rotation of the stop 27 and the platen to which it is connected.

It will be understood from the foregoing description that a relative rotary adjustment between the disks 17 and 19 may be effected and that such adjustment effects a relative adjustment between the stops 25 and 26 and that this adjustment determines the extent of rotation of the stop 27 and therefore the platen when the locking device 33 engages the disk 18 so that the platen is arrested in both its forward and rearward rotation by the stop 27 coacting with the stops 26 and 25, whereas when the locking device 33 is released from the disk 18 the disks 17 and 18 maintain their adjustment relatively to each other by the frictional connection between them and are likewise rotated back and forth with the platen by reason of the frictional connection between said disks and the platen.

The construction of the mechanism for arresting the platen thus far described is essentially the same as that shown and described in the patent to D. A. Carpenter No. 843,071 dated February 5, 1907 and a further description thereof is deemed unnecessary. In the present instance I have provided a spring 35 coiled around the hub of the locking lever 33 (see Fig. 2) and connected at one end to said lever and at the other end to the end plate 7 of the platen frame or carriage. The spring tends to normally maintain the locking lever in the engaged position shown in Fig. 1. The lever may be moved and temporarily held against the tension of the spring in a position where it is disengaged from the disk 18 and when pressure on the lever is released it will be moved back by its spring into engagement

with the disk. The lever may, however, be locked out of engagement with the disk and against the tension of its spring 35. Thus, a combined stop and detent 36 (Fig. 6) is formed on and projects inwardly from the locking lever 33 near its finger piece 34. This member 36 cooperates with a combined stop and locking projection 37 on the end plate 7, or on the forwardly projecting finger piece 7* thereof. The construction is such that a depression by ordinary force exerted on the finger piece 34 will release the locking pawl from the disk 18 and will bring a cam face 36* on the member 36 into contact with a cam face 37* on the stop 37 and will arrest the finger piece against further downward movement. When, however, a greater amount of pressure is applied to the finger piece it results in the forward end of the lever being deflected laterally against its inherent resiliency by the cooperation of the cam faces 36* and 37* to afford a further depression of the forward end of the lever until it reaches the abutment 37* and springs laterally into the locking notch 37* where the lever will be held against return movement. These means are efficient in certain characters of billing work wherein it is desirable to only temporarily release the locking lever and allow it to spring back into locking engagement with the disk 18 under certain conditions and yet the construction is such that the locking lever may be maintained released as long as desired without the necessity of the operator holding it down with the finger. A shouldered screw 38 is employed to connect the cross rod 10 to the right-hand end bar of the platen frame as shown in Fig. 2; and this screw is provided with a bearing portion 39 on which the hub of the locking lever 33 bears and on which the locking lever is mounted to turn, the hub being received between a boss 40 on the platen frame and a circumferential shoulder 39* on the screw 38. The head 41 of the screw 38 is enlarged to form a bearing for one side of a gear wheel 42, said gear wheel being mounted to turn on a shouldered screw 43 received at its threaded end in an opening in the head of the screw 38. The screw 43 also constitutes a pivotal bearing for a carrier 44, the head 45 of said screw constituting a side bearing for the carrier and the carrier bearing at one side against the gear wheel 42. The gear wheel 42 meshes with a pinion 46 formed as a part of the sleeve 15 so that the sleeve constitutes a hub for the pinion. It will thus be seen that the gear 42 is positively geared to the platen shaft and thus is positively connected to the stop 27 and to the platen. The carrier 44 has an extension 47 which carries an adjustable set screw 47*, the latter constituting a stop that is adapted to abut against the platen shaft as shown in Fig. 1 to arrest the

carrier in its rearward movement, whereas an extension 48 of the carrier carries an adjustable set screw 48^a which constitutes a stop adapted to contact with the platen shaft 5 at the end of the forward turning movement of the carrier, thus limiting its movement in that direction.

The carrier 44 is preferably made of sheet metal and has pivoted thereto at 49 two handles or levers 50 normally spring pressed apart as shown in Fig. 1 by a leaf spring 51 secured at one end as at 52 to one of the handles and bearing at its opposite free end against the other handle. The handles are 10 preferably formed of sheet metal and are each bent at right angles to bring the parts 53 thereof into planes parallel to the plane of the carrier 44 and the portions 53 are extended to form engaging devices or pawls 20 54, 55, which co-operate with the gear wheel 42 when the handles are moved relatively to each other on their pivot 49 and are disengaged from the gear wheel by the spring 51 when pressure is released upon the handles. The lower pawl 54 is part of the upper handle 50, and the upper pawl 55 is part of the lower handle 50.

The handles and pawls together form a crank or a device somewhat in the nature 25 of a pair of tongs or pliers, so that when the handles are pressed together the two pawls grip the gear wheel 42 and connect it positively with the carrier 44, or a backward pressure on the forward handle thrusts 30 the pawl 54 into engagement with the gear 42, whereas a forward pressure on the rear handle thrusts the pawl 55 into engagement with the gear. On the other hand, when the finger of the operator is placed between 35 the handles both pawls are maintained out of contact with the gear 42 and the handles and carrier may be swung together around the pivotal center of the carrier. The handles are limited in their movements away from 40 each other by stops 56 which are struck up from and formed as ears upon the carrier 44. These stops project into the paths of movement of the parts 53 of the handles so as to arrest them. The pivot 49 for the 45 handles is preferably in the nature of a shouldered headed screw or bolt (Fig. 3) the threaded end of which co-operates with a nut 57 so that the portions 53 of the handles and the carrier 44 are secured together between 50 the head of the screw 49 and the nut 57. The gearing between the actuating handles 55 and the platen is preferably of such character that a swinging movement of the handles substantially to a horizontal position, or to a position where it is above the top plate and the ribbon spools of the machine (the latter being shown at a in Fig. 1) when moved forward turns the platen 60 as far as is ordinarily required in order to 65 insert a bill into the machine although the

gearing may be changed according to circumstances. By arranging the handles to swing in the manner indicated from the position shown in Fig. 1 to a forward position where the handles remain above the top 70 plate and ribbon spools of the machine, the platen may be rotated by means of the handles at any time irrespective of the position of the carriage and does not interfere with the travel of the carriage when said handles 75 are in the forward position. The extent of movement of the handles indicated is ordinarily enough for billing purposes. If, however, a greater extent of throw is desired the stops 47^a and 48^a may be adjusted 80 to afford the additional movement required.

In the operation of the device the stops 25 and 26 receive a proper relative adjustment and the stops are locked with their disks by the locking lever 33 as shown in Fig. 1. The parts being in the position shown in Fig. 1 the record, carbon and invoice sheets are introduced into the machine with their leading edges together and the handles 50 are moved toward each other, 90 thus effecting an engagement of the pawls 54 and 55 with the gear wheel 42 or a forward pressure may be exerted on the rear handle to cause the pawl 55 to engage the gear. A forward swinging movement of the 95 carrier 44 with the handle is then effected until the stop 27 is moved from the position shown in Fig. 1 to a point where it is brought into contact with the stop 26 when the platen is arrested. This is effected preferably by a single stroke of the handles and carrier, though, if desired, the gear wheel 42 and the parts controlled thereby may be rotated by several strokes of the handles 100 and carrier, the gear being intermittently engaged and disengaged by the pawls. When the stop 27 is brought into contact with the stop 26 the platen and the parts connected therewith are prevented from further forward rotation, the record, carbon 105 and invoice sheets being then in the proper position to receive the first line of writing. The locking device 33 is then actuated to disengage the disk 18, thereby releasing both disks 17 and 18 and the operator proceeds to write the bill or invoice. After the bill is completed the platen is given an additional movement of two line spaces in order to provide a space between the copies of succeeding invoices on the record sheet. 110 The locking device may then be moved to the engaging position to lock both the disks 17 and 18 against further rotation after which the pawls are moved into engagement with the gear wheel 42 by the handles 50 and said handles are moved toward the rear, whereby a rearward movement is given the platen until the stop 27 co-acts with the stop 25. The invoice sheet is then removed without disturbing the carbon and record sheet, 115 120 125 130

a new invoice sheet is introduced into the machine and the platen is turned forwardly in the manner hereinbefore described until said platen is again arrested by the stop 27 striking the stop 26, when the second invoice sheet will be found properly situated with reference to the condensed record sheet, so that the copy of the second invoice on the record sheet will start two line space distances below the last line of the copy of the first bill and the first writing line of the second bill will be at the printing line. These operations may be continued indefinitely or until the condensed record sheet 15 is full, when a new one may be introduced in the manner hereinbefore described. It will be understood that the platen may be rotated by the line spacing mechanism or by the finger wheels 18 at any time without obstruction from the stop devices by releasing the locking device 33 from engagement with the disks 17 and 18. All three of the stops 25, 26 and 27 will in this instance rotate with the platen and the gear wheel 42 will be turned through the rotation of the pinion 46, although the handles and carrier will remain at rest.

The devices hereinbefore described may likewise be used in addressing envelopes 20 and the like and aid in rapidly, efficiently and accurately positioning the envelopes in the machine. In this connection I prefer to employ a coiled restoring spring 58^a hooked at one end over a pin 58^b which projects from the outer face of the carrier 44. The spring surrounds a shouldered capstan screw 58^c received at its threaded end in a tapped opening in the head of the screw 48. The other end portion of the spring is 25 formed as a loop 58^d, the part 58^e thereof bearing against the head of the screw 58^c and adapted to be received and held in a nick 58^f cut therein when said part of the spring is turned rearwardly to place the spring under tension and to register with said nick. Normally the spring may bear on the head of the screw as shown in Fig. 1 and when the carrier is turned forwardly, it turns the spring which is not under tension and carries the ends of the spring forwardly with it. When, however, the devices are to be used to position envelopes in the machine, or for any character of work which requires the carrier to be automatically returned to normal position after each forward movement, the end 58^e of the spring is turned rearwardly until the part 58^e thereof springs into and is locked in the nick 58^f. The effect of this is to place the spring under tension and connect it so as to turn the carrier 44 rearwardly to normal position. The stops having been set so as to arrest the platen in a position where an envelop will properly receive the first line of writing, 30 the envelop is introduced into the machine

and the handles are moved forwardly to turn the platen forwardly until it is arrested by the stops. The handles are released and the pawls 54 and 55 will be disengaged from the gear 42 by the spring 51. The spring 58^a then becomes effective to turn the carrier and handles back to the position shown in Fig. 1. The operator proceeds to address the envelop and withdraws it from the machine after the address is completed. Another envelop is introduced and fed forward as before by turning the handles and the operation continues as before.

It is desirable in certain characters of work to entirely release all of the paper so feeding and guiding devices from contact with the platen in order that the work sheet may be readily moved or adjusted to different positions relatively to the platen. In Figs. 4 and 5 I have shown paper feeding and guiding devices capable of such an operation. From these figures it will be seen that the cross bar 9 is provided with forwardly projecting lugs 56 recessed for the reception of feed roll hangers 60 pivoted at 61 to said lugs. A coiled spring 62 surrounds the pivot of each feed roll hanger and is extended at one end 63 so as to bear against a rearwardly extending projection 64 on the associated hanger, the other end 65 of each spring bearing against the bottom wall in the cut-out or recess in which the hanger is pivoted. The lugs are each extended forwardly as at 66 and apertured to provide a bearing for a rock shaft 67 provided at the left-hand end with a crank arm or finger piece 68 by which the rock shaft may be turned. Collars 69 are fastened to the rock shaft 67 and are provided with projections 70 each of which is situated above and cooperates with one of the hangers 60 when the finger piece is moved rearwardly from the position shown in Fig. 4 in order to turn the hangers on their pivots and to move the feed rollers out of cooperation with the platen as will herein-after more clearly appear. A paper apron 71 is curved to conform substantially to the curvature of the platen and is riveted at 72 to forwardly projecting arms 73 pivoted at 74 to brackets 75 secured by screw 76 to lugs 77 which project forwardly from the cross bar 9. The forward ends of the arms 73 are bent upwardly at 78 where they are riveted as at 79 to a paper scale 80, the upper edge of which bears against the paper apron at the forward edge thereof, the paper apron lying between the platen and the scale and being curved forwardly at the front edge to afford the ready introduction of work sheets from the front of the platen if desired. Arms 81 are pivoted in the lugs 59 and are situated beneath the feed roll hangers 60. These arms are pressed upwardly at their forward ends by 130

springs 82 which surround the pivots 83 of said arms. The forward ends of the arms bear upwardly against the paper apron and normally maintain it with a slight spring pressure against the platen. Spring fingers 84 are riveted to the under side of the paper apron at 85 and project at their free ends beneath the arms 81 so that a downward movement of the arms 81 will carry the paper apron and platen scale away from the platen with said arms. The feed roll hangers support a shaft 86 on which feed rollers 87 are mounted. The feed rollers normally extend through cutouts or openings 87* in the paper apron and contact with the platen as shown in Fig. 4. The lower ends of the hangers extend beyond the feed rollers and are bifurcated for the reception of anti-friction rollers 88 arranged to turn on the pivots 89. These anti-friction rollers bear against the pivoted arms 81 and effect a downward movement thereof when the feed rollers are moved to the inoperative position. Thus, when the finger piece 88 is moved rearwardly from the position shown in Fig. 4 the projections 70 will be forced into contact with the feed roll hangers 80, moving them downwardly against the pressure of their springs. The effect of this is to move the pivoted arms 81 downwardly through the engagement of the rollers 88 with said arms, thereby effecting a bodily movement of the paper apron downwardly away from the platen, the platen scale 80 moving with the paper apron away from the platen. It will be understood that while the parts are in these positions that a free or unobstructed passage is provided around the platen and the work sheet may be readily moved or adjusted relatively to the platen in the passage formed between the platen and the paper apron.

In certain classes of billing work as many as four or five sheets or layers of paper are introduced at one time into the machine at one end of the platen, whereas but a single sheet or layer is introduced at one time into the machine at the other end of the platen. It becomes difficult therefore to properly feed the sheets together. In order to provide an efficient feed of the work sheets under such conditions I have provided a paper apron of resilient metal and slotted the apron at 90 from the forward edge thereof rearwardly back to the points 91 to provide a series of resilient paper fingers 92 which preferably contact with the platen from about the line where the apron contacts with the platen to the forward edge thereof, the fingers hugging the platen snugly and extending transversely thereof and terminating, of course, short of the printing line. By these means the paper apron may be deflected away from the platen at one portion

thereof without being carried away from the platen at another portion thereof so as to conform to the different thicknesses of the work sheet at different points along the platen and effects an efficient feed of the 70 paper.

In practice the line spacing wheel 11 usually has thirty-three teeth in which case the pinion 46 should have thirty-three teeth and the gear 42 should have sixty-six teeth. 75 In short the pinion corresponds to the line spacing wheel and the relation between the gear 42 and the pinion is two to one.

What I claim as new and desire to secure by Letters Patent, is:—

1. In a typewriting machine, the combination of a rotative platen, stop devices for arresting the rotation of the platen, a pinion connected with the platen, a gear meshing with said pinion, a hand actuated crank arm 85 normally disconnected from said gear and that turns in a vertical plane which extends fore and aft of the machine, and means carried by said crank arm for connecting it to and disconnecting it from said gear so that the platen may be turned by said crank arm and may turn independently thereof.

2. In a typewriting machine, the combination of a rotative platen, stop devices for arresting the rotation of the platen, a pinion 95 connected with the platen, a gear meshing with said pinion, a hand actuated crank arm normally disconnected from said gear and that turns in a vertical plane which extends fore and aft of the machine, means carried 100 by said crank arm for connecting it to and disconnecting it from said gear so that the platen may be turned by said crank arm and may turn independently thereof, stops carried by said crank arm, and a relatively fixed 105 cooperating stop to limit the back and forth movements of said crank arm.

3. In a typewriting machine, the combination of a rotative platen, stop devices to arrest the rotation of the platen, two handles pivoted for relative movement, means for operatively connecting at will the platen to rotate with said handles, the actuation of said connecting means being controlled by a relative pivotal movement of the handles. 110

4. In a typewriting machine, the combination of a rotative platen, and actuating means for rotating said platen and for affording a rotation of the platen independently of said actuating means, said actuating 120 means comprising a pivoted carrier, two handles pivoted to said carrier, and engaging devices actuated by said handles, a relative movement between the handles being effective to operate said engaging devices to 125 operatively connect the handles to the platen.

5. In a typewriting machine, the combination of a rotative platen, and actuating means for rotating said platen and for affording a rotation of the platen independ- 130

ently of said actuating means, said actuating means comprising a gear operatively connected with the platen, a pivoted carrier, two handles pivoted to said carrier, and engaging pawls controlled by said handles and adapted to be forced into and out of engagement with said gear by relative movements of said handles on their carrier.

6. In a typewriting machine, the combination of a rotative platen, an actuating means for rotating said platen and for affording a rotation of the platen independently of said actuating means, said actuating means comprising a pinion connected with the platen, a gear meshing with said pinion, a pivoted carrier, two handles pivoted to said carrier, and engaging pawls controlled by said handles and adapted to be forced into and out of engagement with said gear by relative movements of said handles on their carrier.

7. In a typewriting machine, the combination of a rotative platen and actuating means for rotating said platen and for affording a rotation of the platen independently of said actuating means, said actuating means comprising a pinion secured to the platen shaft, a gear meshing with said pinion, a carrier pivoted at the same axis as said gear, two handles pivoted to said carrier and spring pressed to normal position thereon, and a pawl actuated by each handle and adapted to be engaged and disengaged from said gear by relative movements of said handles on their carrier.

8. In a typewriting machine, the combination of a rotative platen, and actuating means for rotating said platen and for affording a rotation of the platen independently of said actuating means, said actuating means comprising a pinion secured to the platen shaft, a gear meshing with said pinion, a carrier pivoted at the same axis as said gear, stops to limit the movement of said carrier, two handles pivoted to said carrier and spring pressed to normal position thereon, stops on said carrier to limit the movements of the handles relatively thereto, and a pawl actuated by each handle and adapted to be engaged and disengaged from said gear by relative movements of said handles on their carrier.

9. In a typewriting machine, the combination of a rotative platen, and actuating means for rotating said platen and for affording a rotation of the platen independently of said actuating means, said actuating means comprising a pair of pivoted spring separated handles each carrying a rigidly connected engaging device, said engaging devices being adapted to be thrown into operative connection with the platen by a relative movement of the handles toward each other.

10. In a typewriting machine, the combi-

nation of a rotative platen and actuating means for rotating said platen and for affording a rotation of the platen independently of said actuating means, said actuating means comprising a pinion secured to the platen shaft, a gear meshing with said pinion, a carrier pivoted at the same axis as said gear, two spring separated handles pivoted to said carrier and each carrying a rigidly connected pawl, said pawls being adapted to be thrown into engagement with said gear by a relative movement of the handles toward each other.

11. In a typewriting machine, the combination of a rotative platen, platen actuating means comprising a crank arm and means carried by the crank arm for effecting a connection and disconnection between said crank arm and said platen at will at any position in the movement of the crank; and platen arresting mechanism independent of the crank, said platen arresting mechanism including a rotary stop which is normally movable with the platen to an indefinite extent in either direction, means for locking said stop in different positions, and a co-operating stop positively connected with the platen.

12. In a typewriting machine, the combination of a rotative platen; actuating means for rotating said platen and for affording a rotation of the platen independently of said actuating means, said actuating means comprising a pivoted carrier, two handles pivoted to said carrier, and engaging devices actuated by said handles, a relative movement between the handles being elective to operate said engaging devices to operatively connect the handles to the platen; and stop devices for arresting the rotation of the platen.

13. In a typewriting machine, the combination of a rotative platen; actuating means for rotating said platen and for affording a rotation of the platen independently of said actuating means, said actuating means comprising a gear operatively connected with the platen, a pivoted carrier, two handles pivoted to said carrier, and engaging pawls controlled by said handles and adapted to be forced into and out of engagement with said gear by relative movements of said handles on their carrier, and stop devices for arresting the rotation of the platen.

14. In a typewriting machine, the combination of a rotative platen; actuating means for rotating said platen and for affording a rotation of the platen independently of said actuating means, said actuating means comprising a pinion connected with the platen, a gear meshing with said pinion, a pivoted carrier, two handles pivoted to said carrier, and engaging pawls controlled by said handles and adapted to be forced into and out of engagement with said gear by

relative movements of said handles on their carrier, and stop devices for arresting the rotation of the platen.

15. In a typewriting machine, the combination of a rotative platen; actuating means for rotating said platen and for affording a rotation of the platen independently of said actuating means, said actuating means comprising a pinion secured to the platen shaft, a gear meshing with said pinion, a carrier pivoted at the same axis as said gear, two handles pivoted to said carrier and spring pressed to normal position thereon, and a pawl actuated by each handle and adapted to be engaged and disengaged from said gear by relative movements of said handles on their carrier, and stop devices for arresting the rotation of the platen.

16. In a typewriting machine, the combination of a rotative platen; actuating means for rotating said platen and for affording a rotation of the platen independently of said actuating means, said actuating means comprising a pinion secured to the platen shaft, a gear meshing with said pinion, a carrier pivoted at the same axis as said gear, stops to limit the movements of said carrier, two handles pivoted to said carrier and spring pressed to normal position thereon, stops on said carrier to limit the movements of the handles relatively thereon and a pawl actuated by each handle and adapted to be engaged and disengaged from said gear by relative movements of said handles on their carrier; and stop devices for arresting the platen.

17. In a typewriting machine, the combination of a rotative platen; actuating means for rotating said platen and for affording a rotation of the platen independently of said actuating means, said actuating means comprising a pair of pivoted spring separated handles each carrying a rigidly connected engaging device, said engaging devices being adapted to be thrown into operative connection with the platen by a relative movement of the handles toward each other, and stop devices for arresting the rotation of the platen.

18. In a typewriting machine, the combination of a rotative platen; actuating means for rotating said platen and for affording a rotation of the platen independently of said actuating means, said actuating means comprising a pinion secured to the platen shaft, a gear meshing with said pinion, a carrier pivoted at the same axis as said gear, stops to limit the movement of said carrier, two spring separated handles pivoted to said carrier and each carrying a rigidly connected pawl, said pawls being adapted to be thrown into engagement with said gear by a relative movement of the handles toward each other; and stop devices for arresting the rotation of the platen.

19. In a typewriting machine, the combination of a rotative platen; actuating means for rotating said platen and for affording a rotation of the platen independently of said actuating means, said actuating means comprising a pivoted carrier, two handles pivoted to said carrier, and engaging devices actuated by said handles, a relative movement between the handles being effective to operate said engaging devices to operatively connect the handles to the platen; and platen arresting mechanism including a rotary stop which is normally movable with the platen to an indefinite extent in either direction, means for locking said stop in different positions, and a co-operating stop positively connected with the platen.

20. In a typewriting machine, the combination of a rotative platen; actuating means for rotating said platen and for affording a rotation of the platen independently of said actuating means, said actuating means comprising a gear operatively connected with the platen, a pivoted carrier, two handles pivoted to said carrier, and engaging pawls controlled by said handles and adapted to be forced into and out of engagement with said gear by relative movements of said handles on their carrier; and platen arresting mechanism including a rotary stop which is normally movable with the platen to an indefinite extent in either direction, means for locking said stop in different positions, and a co-operating stop positively connected with the platen.

21. In a typewriting machine, the combination of a rotative platen; actuating means for rotating said platen and for affording a rotation of the platen independently of said actuating means, said actuating means comprising a pinion connected with the platen, a gear meshing with said pinion, a pivoted carrier, two handles pivoted to said carrier, and engaging pawls controlled by said handles and adapted to be forced into and out of engagement with said gear by relative movements of said handles on their carrier; and platen arresting mechanism including a rotary stop which is normally movable with the platen to an indefinite extent in either direction, means for locking said stop in different positions, and a co-operating stop positively connected with the platen.

22. In a typewriting machine, the combination of a rotative platen; actuating means for rotating said platen and for affording a rotation of the platen independently of said actuating means, said actuating means comprising a pinion secured to the platen shaft, a gear meshing with said pinion, a carrier pivoted at the same axis as said gear, two handles pivoted to said carrier and spring pressed to normal position thereon, and a pawl actuated by each handle and adapted to be engaged and disengaged from said

gear by relative movements of said handles on their carriers; and platen arresting mechanism including a rotary stop which is normally movable with the platen to an indefinite extent in either direction, means for locking said stop in different positions, and a coöperating stop positively connected with the platen.

23. In a typewriting machine, the combination of a rotative platen; actuating means for rotating said platen and for affording a rotation of the platen independently of said actuating means, said actuating means comprising a pinion secured to the platen shaft, a gear meshing with said pinion, a carrier pivoted at the same axis as said gear, stops to limit the movements of said carrier, two handles pivoted to said carrier and spring pressed to normal position thereon, stops on said carrier to limit the movements of the handles relatively thereto, and a pawl actuated by each handle and adapted to be engaged and disengaged from said gear by relative movements of said handles on their carrier; and platen arresting mechanism including a rotary stop which is normally movable with the platen to an indefinite extent in either direction, means for locking said stop in different positions, and a coöperating stop positively connected with the platen.

24. In a typewriting machine, the combination of a rotative platen; actuating means for rotating said platen and for affording a rotation of the platen independently of said actuating means, said actuating means comprising a pair of pivoted spring separated handles each carrying a rigidly connected engaging device, said engaging devices being adapted to be thrown into operative connection with the platen by a relative movement of the handles toward each other; and platen arresting mechanism including a rotary stop which is normally movable with the platen to an indefinite extent in either direction, means for locking said stop in different positions and a coöperating stop positively connected with the platen.

25. In a typewriting machine, the combination of a rotative platen; actuating means for rotating said platen and for affording a rotation of the platen independently of said actuating means, said actuating means comprising a pinion secured to the platen shaft, a gear meshing with said pinion, a carrier pivoted at the same axis as said gear, stops to limit the movements of said carrier, two spring separated handles pivoted to said carrier and each carrying a rigidly connected pawl, said pawls being adapted to be thrown into engagement with said gear by a relative movement of the handles toward each other; and platen arresting mechanism including a rotary stop which is normally movable with the platen to an indefinite ex-

tent in either direction, means for locking said stop in different positions, and a coöperating stop positively connected with the platen.

26. In a typewriting machine, the combination of a rotative platen, stop devices for arresting the platen, a crank for turning the platen, means for automatically establishing an operative connection and disconnection between said crank and the platen by a movement of said crank, and spring means for restoring said crank to one of the limits of its platen turning movements independently of the platen.

27. In a typewriting machine, the combination of a rotative platen, stop devices for arresting the platen, a crank for turning the platen, means for automatically establishing an operative connection between said crank and the platen by a movement of said crank, spring means for restoring said crank to one of the limits of its platen turning movements, and means for rendering said spring means operative or inoperative at will.

28. In a typewriting machine, the combination of a rotative platen; stop devices for arresting the platen; a crank for turning the platen, said crank comprising two handles mounted for relative movement; means for establishing an operative connection between said crank and platen by a relative movement of said handles; and spring means for restoring said crank to the limit of its platen turning movement in one direction independently of the platen.

29. In a typewriting machine, the combination of a rotative platen; stop devices for arresting the platen; a crank for turning the platen, said crank comprising two handles mounted for relative movement; means for establishing an operative connection between said crank and platen, by a relative movement of said handles; spring means for restoring said crank to the limit of its platen turning movement in one direction; and means for rendering said spring means operative or inoperative at will.

30. In a typewriting machine, the combination of a rotative platen; stop devices for arresting the platen; a crank for turning the platen, said crank comprising two handles mounted for relative movement, a carrier for said handles; means for establishing an operative connection and disconnection between said crank and platen by a relative movement of said handles; spring means co-operative with said carrier for restoring said crank to the limit of its platen turning movement in one direction independently of the platen.

31. In a typewriting machine, the combination of a rotative platen; stop devices for arresting the platen; a crank for turning the platen, said crank comprising two handles mounted for relative movement, a carrier

- for said handles; means for establishing an operative connection between said crank and platen by a relative movement of said handles; spring means co-operative with said carrier for restoring said crank to the limit of its platen turning movement in one direction; and means for rendering said spring means operative or inoperative at will on said carrier.
32. In a typewriting machine, the combination of a rotative platen; a gear operatively connected to the platen; stop devices for arresting said platen; a crank for turning the platen, said crank comprising a pivoted carrier, two relatively movable handles pivoted to said carrier; a pawl carried by each handle and co-operative with said gear; and a spring connected to said carrier to restore it to normal position.
33. In a typewriting machine, the combination of a platen; a paper apron; a platen scale; a pivoted arm which carries said paper apron and platen scale; spring means for maintaining the paper apron against the platen; paper feed rollers; hangers for said feed rollers, said hangers being independent of the paper apron, one of said hangers being co-operative with said spring means; and hand actuated means for moving said hangers, thereby moving the feed rollers, paper apron and paper scale away from the platen.
34. In a typewriting machine, the combination of a platen; paper feed rollers; a platen scale; a paper apron; movable arms on which said paper apron and platen scale are supported; hangers for said feed rollers, said hangers being independent of the paper apron; spring means for forcing the paper feed rollers, paper apron and platen scale toward the platen; hand actuated means co-operative with said hangers for forcing the feed rollers away from the platen; and means whereby the releasing movement of the hangers is effective to move the paper apron and platen scale away from the platen.
35. In a typewriting machine, the combination of a platen; paper feed rollers; a platen scale; a paper apron; pivoted supporting arms to which the paper apron and platen scale are fixed; pivoted spring pressed arms that force the paper apron and platen scale toward the platen; pivoted spring pressed hangers for said feed rollers, said hangers co-operating with said spring pressed arms; and hand actuated means co-operative with said hangers for moving them against their spring pressure, thereby moving the feed rollers, the paper apron and the platen scale away from the platen.
36. In a typewriting machine, the combination of a platen; a paper apron; a platen scale; supporting arms which are pivoted at their rear ends and extend beneath the platen and are bent at their forward ends, the platen scale being secured to the bent ends of said arms and the paper apron being secured to the arms intermediate of their ends; and hand actuated means for controlling the movement of said arms around their pivots.
37. In a typewriting machine, the combination of a platen; a paper apron; a platen scale; supporting arms which are pivoted at their rear ends and extend beneath the platen and are bent at their forward ends, the platen scale being secured to the bent ends of said arms and the paper apron being secured to the arms intermediate of their ends; paper feed rollers; hangers for said feed rollers, said hangers controlling the movement of said arms away from the platen; and hand actuated means for controlling the movements of said hangers.

Signed at Toronto, Province of Ontario, in the county of York, and Dominion of Canada, this 11th day of November A. D. 1907.
